Primary Examiner — T Chase Nelson*Assistant Examiner* — Mary Claire Ramirez(74) *Attorney, Agent, or Firm* — AWA Sweden AB;
Thomas L. Ewing(57) **CLAIM**

The ornamental design for an in-ear device, as shown and described.

DESCRIPTION

FIG. 1 is a front right side perspective view of an in-ear device showing our new design;

FIG. 2 is a front view thereof;

FIG. 3 is a right view thereof;

FIG. 4 is a left view thereof;

FIG. 5 is a bottom, left perspective view thereof;

FIG. 6 is a bottom plan view thereof; and,

FIG. 7 is a top plan view thereof.

The broken lines shown in the drawings depict portions of the in-ear device that form no part of the claimed design.

1 Claim, 4 Drawing Sheets# US D883,491 S
